CLAIM

I claim the ornamental design for a resilient jaw support, as shown and described.

DESCRIPTION

FIG. 1 is a view in side elevation of a resilient jaw support embodying my new design, the other side being a mirror image thereof;

FIG. 2 is a perspective view thereof;

FIG. 3 is a top plan view thereof; and,

FIG. 4 is a bottom plan view thereof.

The broken lines of FIG. 1 showing the head of a wearer of the resilient jaw support are for illustrative purposes only and form no part of the claimed design.
